EXPANSION BIT

John W. Jacobs, Seattle, Wash.

Application January 30, 1956, Serial No. 562,085

2 Claims. (Cl. 145—127)

This present invention relates to the general art of wood boring bits and more particularly to an expansion bit. This design is further characterized by means which greatly facilitate the accurate expanding or retraction of the movable cutters and when they are properly positioned and their diametrical distance has been adequately checked, means are provided for adequately locking the actuating mechanism so that the entire assembly is definitely locked against any change of adjustments.

Expansion bits have been employed by carpenters and others working in wood for many years and many different styles have been produced. This present invention follows certain of the principles formerly employed, namely that in the preferred form two opposed cutters are employed which are adjustable along their longitudinal axis so that a wide range of hole sizes can be bored with the device. In the past a most common fault with extension bits has been the inability to provide adequate adjusting and securing means. A common form has been merely to have the cutters longitudinally adjustable in metal recesses or slots and then to have some form of a locking screw to bind them in the adjusted position. Some attempts have been made further to employ rack gears cut on the cutters themselves and with a spur gear pinion adapted to engage the same either as a component of the bit or as a unit temporarily applied to the adjustment of the cutters. Such means have a common fault with the simpler forms in that there is no definite locking of the bit in its extended position.

In my present expansion bit I employ teeth cut on the upper edge of the cutter bars but form these teeth with adequate clearance so that the actuating means which is a worm or screw thread will engage the teeth in a manner so that there is no end or longitudinal movement possible in the cutter bars. This arrangement is in effect a single thread worm gear of which parts have been cut away in forming the operational parts of this device. The outstanding characteristic of the single thread worm, namely that it is self-locking, is however retained in this construction so that any tendency for the cutter to crowd away from hard spots, in either direction, from its adjusted position is met by the worm which holds it against movement. Further, the locking of the cutter bar rack by the spiral thread arrangement provides such a small angle of force application that there is no possibility of pressure on the cutter tooth actually turning the actuating and positioning worm or threaded nut. It follows therefore that when the bit is adjusted it is only necessary to provide some form of functional lock for the screw thread nut in order to insure that it is not moved as might occur in laying the tool down or something of that order. In other words the final locking means merely secures the actuating worm against movement and in this way a very secure locking of the tool is provided.

In the past carpenters have been greatly inconvenienced by the fact that once they would start a large hole, for

2

instance in a door for the installation of a lock, they had little if any way of having an indication of any change in the cutting diameter of the bit until it emerged from the opposite side of the door. There are few carpenters that have not had the experience of actually spoiling doors and like finished work parts by having the bit change its cutting diameter and thus in many cases provide an exit opening of larger diameter which in many cases could not be covered by the fittings of the lock or the diameter would be reduced so a conical hole was produced and this would require reworking as with rasps and the like in order that the lock could be fitted. All these faults are either annoying or destroy expensive parts or consume a great deal of time which in turn is quite valuable on the present labor market. In my present expansion bit it is believed that a great many of the outstanding deficiencies of the present forms of expansion bits have been overcome and a bit provided that will insure the most exacting work with the minimum of expenditure of time.

The principal object of this invention therefor is to provide an expansion bit that is easily adjusted to exact dimension and when once adjusted can be securely locked in its adjusted position.

A further object of this present invention is to provide a positioning and securing means for an extendable cutting blade which makes use of the self-locking principles of a single thread worm to the end that secure locking of the device can be depended upon.

A further object of this present invention is to provide locking means for extendable cutter bits in an extension tool in which the main positioning and locking means is further provided with a secondary lock to the end that the device can be depended upon to maintain this extended position throughout an entire operation.

A further object of this present invention is to provide an expandable bit employing two opposed cutters to the end that the cutting circle can be accurately measured and set in the desired position.

Further objects, advantages and capabilities will be apparent from the description and disclosure in the drawings, or may be comprehended or are inherent in the device.

Figure 1 is a perspective view showing a preferred form of my present invention with certain parts being shown in section.

Figure 2 is a side elevation, partly in section, of the form of my tool as illustrated in Figure 1.

Figure 3 is an elevational view taken as though the device of Figure 2 were revolved 90 degrees and with certain parts shown in section and in dashed lines to better illustrate the construction. The irregular cutting plane is substantially through the center of the device of Figure 2.

Figure 4 is an elevation view, partly in section, illustrating a modified form of my device in which only one cutter is employed.

Figure 5 is an elevation, partly in section, to illustrate the internal structure, the showing being revolved 90 degrees from the position of Figure 4.

Figure 6 is a perspective view, partly in section, illustrative of the cupped tensioning washer employed to assist in securing the locking means in its locked position.

Figure 7 is a face view of my work type actuating nut showing the spiral or worm gear teeth employed in this device.

Referring more particularly to the disclosure in the drawings, the numeral 10 designates the central or auger body of my tool. This is provided with an upwardly extending shank as 12 which may be left cylindrical in form for use with power tools or it may be provided

with the conventional four sided tapered end that is characteristic of ordinary wood bits and adapts the same for use in hand operated carpenter's braces. The lower body of member 10 terminates in a lead screw 14 of a type normally employed on wood bits, augers and the like. Positioned above lead screw portion 14 is a cutter member 16 and a spiral grooved portion 18. This arrangement insures that the body portion of my expansion bit will have its own means of disposing of the wood in its path so that it may progress through the wood being bored and make it possible for the extendable cutters to be led into the wood with adequate pressure to insure their biting in and boring through the piece.

Member 10 is slotted to accept either the two extendable cutters as 20 and 22 of the preferred form of my invention or it may be slotted for the single cutter as 24, illustrated in the modified form of my device in Figures 4 and 5. In all the forms, cutters 20, 22 and 24 are disposed at an angle to the vertical axis substantially as illustrated in Figures 3 and 5 to the end that the initial cutter element 25 may engage the wood first and then the main cutting edge 27 of the cutter blade itself successively engages the wood so that the hole is outlined at the start and all cross-grained wood prevented from splitting outside the hole being bored. This inclination of the cutters calls for similar disposition of the slots as 26 and 28 of the double or preferred form and 30 in the single cutter form. These slots provide a snug but workable engagement of the cutters on both sides as well as the edges which are actually more critical. The portion between shank 12 and the enlarged portion in which the various slots occur is preferably threaded as at 32 with a relatively fine thread so that the locking nut member 34 or 54 can be securely seated. Because of the relatively flat pitch which is a function of the fine threads there will be little tendency for the nut to loosen and this can be met by providing a bar washer, bent on a single axis, as 36, which will at all times, keep the nut tight against the threaded portion 32.

The enlarged portion of the auger member 10 is provided with a ledge-like seat as 38 and is provided with a bore as 40 of reduced diameter so that the worm or spiral threaded ring 42 will be centered and positioned in its operational relationship with the cutter members as 20, 22, and 24. Annular engaging member 42 is preferably counter-bored so as to accept a reduced diameter portion of the lock nut 34 or 54. This relationship is quite well illustrated in Figures 3 and 5 of the drawings. The outer surfaces of member 42 and nut 34 are preferably knurled so that hand manipulation of these members will be facilitated. It is to be noted that in the operation of my device that hand operation is all that is required for the security of the elements in their locked or adjusted positions, it not being necessary to employ wrenches as are so often used with other types of this equipment.

As it will be noted in Figures 3 and 5 the lower surface of adjusting member 42 takes on the same angle with respect to the vertical axis of the device as the cutters as 20, 22 or 24 that it engages. It is noteworthy that the inclination of the cutters makes it possible for ring-like member 42 to engage teeth 43 of the cutter only at one point, consequently this angular relationship is easily maintained and makes for snug engagement which in turn means accurate adjustment that will be readily maintainable over long periods of use. The annular engaging member 42 is provided with a spirally arranged gear tooth or groove 44. The arrangement of these grooves however, actually produces the tooth-like forms illustrated in Figures 3 and 5. This tooth disposed on the relatively large diameter acts in the same manner as a spiral or worm gear in that the angularity between the teeth formed on device 42 and the teeth 43 of the various racks is so slight that no normal amount of pressure on the cutters can revolve member 42 and change the adjust-

ment. This is a very important characteristic of this present invention. It is to be noted that the adjustment of the cutters by means of the adjusting member 42 is easily affected with the unaided fingers and then when an adjusted position has been obtained the lock-nut 34 which is provided with a relatively fine, or so-called automobile thread 32 can easily be seated tightly enough with the unaided fingers so that the whole unit is a securely, locked in position, assembly. It is to be noted that in the modified form shown in Figures 4 and 5 this bare hand setting of the locking member has been substituted for by the locking member 54 which is otherwise similar but is provided with a shortened thread area 56 and the actual turning of the lock nut is accomplished by a spanner wrench which fits the detent openings as 58 formed in the nut member. This arrangement is intended more for use in power equipment where the device might be set up for a definite size hole and left in that adjusted position for many successive periods of use.

Referring to the preferred form shown in Figures 1, 2 and 3 it is to be noted that cutters 20 and 22 are positioned in communicating slots 26 and 28 in a back-to-back arrangement; however the positioning slots 26 and 28 are oppositely pitched after the showing of Figure 3 so that for a good portion of their extent they are in effect separate slots which are merely brought together at their mid portions in order to facilitate machining and to bring the two cutters close together so that a more diametrical position of the opposed cutter points 25 can be achieved.

It is believed that it will be clearly apparent from the above description and the disclosure in the drawings that the invention comprehends a novel construction of an expansion wood bit.

Having thus disclosed the invention, I claim:

1. An expansion wood bit, comprising: a central auger member having an upwardly extending shank, a lower body and a bottom lead screw, said auger body having a slot extending transversely therethrough and angularly disposed with the longitudinal axis of said auger member; an extendable cutter bar slidably mounted in said through slot, said cutter bar having a depending sharpened cutter tooth at one end and forming an obtuse angle with the longitudinal axis of said shank and having a cutting edge extending from said tooth along the lower margin of one face thereof; said cutter bar having teeth with their faces extending transversely thereof and formed in a row extending along the cutter's upper surface; an annular engaging member having an engaging face angularly disposed to make a full engagement with the faces of said teeth of the cutter bar, mounted coaxially on said auger body and manually operable to engage said upper teeth of said cutter bar on one side only of said annular engaging member to hold the cutter bar against movement along its longitudinal axis; said annular engaging member having tooth engaging portions which are near right-angular with respect to the cutter bar longitudinal axis so that the pressure of the cutter upper teeth thereagainst will have little camming action to displace the engaging member transversely to the side; said annular engaging member having spirally disposed groove means on its lower surface which form the tooth engaging portions for the cutter bar upper teeth; said annular member being rotatably mounted on said auger body and the spiral groove having sufficient inclination, relative said upper teeth faces, to move said cutter bar in said slot as said annular engaging member is rotated; and locking means for holding said annular member against rotary displacement consisting of a locking nut rotatably mounted on said auger shank and having threaded connection therewith whereby the locking nut may be tightened to press said annular engaging member against said cutter bar to frictionally hold the same against rotation.
2. An expansion wood bit, comprising: an auger body and a shank upwardly extending therefrom and a bottom

lead screw on said auger body, a pair of through slots extending transversely through said auger body and slanted oppositely relative the horizontal and said through slots being juxtaposed and being in communication in their central portions, a pair of extendable cutter bars disposed in said through slots, slanted at different angles regarding each other by the inclination of said through slots and said cutter bars having their abutting sides in contact throughout their central portions; said cutter bars each having a depending sharpened cutter tooth at its lower outer end and having a cutting edge along the lower margin of one face, said cutter bars each having a series of teeth disposed along its upper edge with the tooth faces oriented transversely of the cutter bars, said auger body having an annular locking ring rotatably mounted on its upper portion and the locking ring having spiral groove means on its bottom disposed in a plane normal to the longitudinal axis of said auger body engaged with the adjacent teeth of said cutter bars, the groove means on said locking ring having only slight inclination relative 20 the faces of the cutter bar teeth whereby pressures on said locking ring by said cutter bars have little camming

force on said ring to rotate the same, said locking ring being manually rotatable and moving the cutter bars an equal distance inward and outward upon rotation thereof; a locking nut abutting the upper portion of said locking ring and said nut having a central opening having threaded engagement with said auger shank and said locking nut being rotatable to press against locking ring to frictionally hold the locking ring against rotation.
